[57] CLAIM

The ornamental design for a pitcher, as shown.

DESCRIPTION

FIG. 1 is a top, front and left side perspective view of a
pitcher showing my new design;

FIG. 2 is a top plan view;

FIG. 3 is a left side elevation with the opposite side
being a mirror image thereof;

FIG. 4 is a section of the pitcher handle taken along line
4—4 of FIG. 3;

FIG. 5 is a fragmentary rear elevation; and

FIG. 6 is a section of the bottom of the pitcher taken
along line 6—6 of FIG. 3.
